UNITED STATES PATENT OFFICE.

ADOLPH R. HOEFFT, OF CHICAGO, ILLINOIS.

COMBINED BOTTLE-CAP REMOVER AND STOPPER.

959,220.

Specification of Letters Patent. Patented May 24, 1910.

Application filed June 1, 1909. Serial No. 499,514.

To all whom it may concern:

Be it known that I, ADOLPH R. HOEFFT, a citizen of the United States, and a resident of Chicago, in the county of Cook and State 5 of Illinois, have invented certain new and useful Improvements in Combined Bottle-Cap Removers and Stoppers; and I do hereby declare that the following is a full, clear, and exact description thereof, reference being had to the accompanying drawings, and 10 to the characters of reference marked thereon, which form a part of this specification.

This invention relates to a novel combined bottle cap remover and stopper, designed 15 to remove the sheet metal caps from bottles containing a charged beverage and to thereafter close the bottle against escape of the charging gas during subsequent withdrawal of the beverage from time to time.

20 The object of the invention is to provide an exceedingly simple device of the character, which is strong and durable and which may be made at small cost.

A further object of the invention is to 25 provide a neat and attractive device of this character which is of such weight and size as to permit it to be practically carried as a pocket piece, as well as to be used at soda fountains and bars, and which presents a 30 large surface available to receive advertising matter.

The invention consists in the matters hereinafter set forth and more particularly pointed out in the appended claims.

35 In the drawings, Figure 1 is a top perspective view of the combined bottle cap remover and stopper embodying my invention. Fig. 2 is a top plan view thereof. Figs. 3 and 4 are cross sections on lines 3—3 and 4—4 respectively of Fig. 2. Fig. 5 illustrates the 40 manner of removing a sheet metal cap from a bottle by the use of my device. Fig. 6 illustrates the position of the device on the bottle when serving as a stopper or closure 45 therefor.

As shown in the drawings, 10 designates the device as a whole. It comprises a sheet steel plate 11, made slightly larger at one end than at the other, and is provided at 50 its larger end with an opening 12 and at its other end with a stopper 13 detachably fitted to the lower side thereof. As herein shown the plate is flat, and it is provided at its side margins with downwardly turned stiffening 55 flanges 14 which extend from the curved

larger end 15 of the device to within a short distance of the smaller curved end 16 thereof.

The stopper 13, which may be made of cork or other suitable compressible material, is fitted at its base to the under side of the 60 plate 11, and as herein shown is located closely adjacent to the smaller end of the plate, though arrangement may be somewhat varied if desired. The stopper is attached to the plate by means of a headed screw 17 65 which extends through an opening in the plate, through an axial opening in the stopper and has screw threaded engagement with an interiorly screw-threaded nipple 18 formed integral with a disk 19 that is fitted 70 to the inner end face of the stopper. The disk may be made of sheet metal with the nipple struck up therefrom, and is herein shown as slightly concave with its rim arranged to bite into the end of the stopper. 75 This arrangement prevents gas from escaping outwardly between the disk and stopper and through the axial opening of the stopper.

In order to prevent the stopper rotating about the axis of its attaching screw, and 80 thus avoid tendency of the clamping disk being turned off the screw, I provide an interlocking connection between the plate and base of the stopper. This is shown as effected striking one or more prongs or 85 spurs 20 downwardly from the plate so as to be embedded in the base of the stopper. Two of such spurs are herein shown, they being located between the attaching screw 17 and the smaller end of the plate. Such 90 interlocking projections are formed in the plate without additional expense after the die has been made.

The manner of using the device to remove a metal cap from a bottle is shown in Fig. 5. 95 As shown in said figure the cap is removed by a lifting operation. That is to say, the plate is placed with the opening 12 over one side of the cap 21 with the margin or lip 22 at the inner side of said opening engaged 100 under the flaring edge 23 of the cap and with other margins of said opening bearing against the top of the cap. By lifting the outer end of the device from the position shown in Fig. 5 the cap is lifted off the 105 bottle neck. If desired the plate may be placed over the cap with its other margin (or the lug 24 formed on said margin) engaged with the lower flaring edge of the cap and the margin 22 engaged with the top of 110

- the cap; and in this position of the device the cap is removed by a prying operation or depressing the outer, stopper carrying end of the plate.
- 5 In order that the side portions 25, 25 of the plate at the sides of the opening 12 may be strengthened against bending in the use of the device, the stiffening flanges 14 may be widened or deepened as shown at 26.
- 10 Similarly the portion of the plate between the opening 12 and the end margin 15 of the plate may be strengthened by the formation of a transverse bead 27 in this part of the plate. The employment of such stiffening or reënforcing means admits of the use 15 of lighter gage metal, without sacrificing the strength of the device.
- In Fig. 6 is shown the use of the device as a stopper, the stopper 13 being inserted 20 into and closing the mouth of the bottle. The cork is made to closely fit the standard bottle mouth, and when in place prevents the escape of the charging gas from the beverage in the bottle.
- 25 The construction and arrangement of the device provides on the front face thereof a large space to receive an advertising announcement, such as the advertisement of the manufacturer or bottler of a particular 20 charged beverage. This feature of the device adds great value to it in addition to its utility as a means of removing bottle caps and thereafter closing the bottles while the contents are used from time to time. The 35 simplicity of the device and its small cost of manufacture are important features of advantage in both of these phases of its use.
- It will be understood that the structural details of the device may be slightly varied
- within the scope of the claims hereto appended and I do not wish to be limited to the exact details except as hereinafter made the subject of specific claims.
- I claim as my invention:
1. A combined bottle cap remover and bottle closure comprising a flat sheet metal plate formed at one end with the opening 12, one margin of which constitutes a bottle cap engaging lip and provided at the side margins of its imperforate part with the narrow stiffening flanges 14 and at the sides of said opening with the deeper stiffening flanges 26 and between said opening and the adjacent end margin with the stiffening bead 27 and a separately formed stopper 55 fixed to and extending at right angles from the flange of said plate and designed to enter a bottle mouth.
2. A combined bottle cap remover and bottle closure comprising, in combination 60 with a sheet metal plate provided at one end with cap removing means, of a yieldable stopper at the other end of the plate, clamping means extending axially through the stopper and through an opening in the plate 65 for clamping the stopper on the plate and spurs struck up from the plate and embedded in the base of the yieldable stopper to prevent turning of the stopper about its axis.
- In testimony, that I claim the foregoing as my invention I affix my signature in the presence of two witnesses, this 26th day of May A. D. 1909.
- ADOLPH R. HOEFT.
